UNITED STATES PATENT OFFICE

161,379

PORTABLE RADIO RECEIVER

Peter Schladermundt, Bronxville, N. Y., and
 Charles L. Metzler, Palisades, N. J., assignors to
 Avco Manufacturing Corporation, Cincinnati,
 Ohio, a corporation of Delaware

Application June 3, 1949, Serial No. 3,041

Term of patent 3½ years

(Cl. D56—4)

To all whom it may concern:

Be it known that we, Peter Schladermundt, a citizen of the United States, residing at Bronxville, New York, in the county of Westchester, and Charles L. Metzler, a citizen of the United States, residing at Palisades, New Jersey, in the county of Warren, have invented a new, original, and ornamental Design for a Portable Radio Receiver, of which the following is a specification, reference being had to the accompanying drawing, forming a part thereof.

Figure 1 is a perspective view of the front and top panels of a portable radio receiver showing our new design;

Figure 2 is a perspective view showing the top and side panels of the cabinet of Figure 1;

Figure 3 is a perspective view showing the rear and top panels of our radio receiver cabinet; and

Fig. 4 is an elevational sectional view taken along the line 4—4 of Fig. 1, looking in the direction of the arrows.

The dominant features of our design reside in that portion shown in full lines in the drawing.

We claim:

The ornamental design for a portable radio receiver, as shown and described.

PETER SCHLADERMUNDT.

CHARLES L. METZLER.
